UNITED STATES PATENT OFFICE.

CHARLES M. PALMER, OF CHICAGO, ILLINOIS.

ROLLER-SKATE.

No. 873,889.

Specification of Letters Patent.

Patented Dec. 17, 1907.

Application filed April 20, 1907. Serial No. 369,287.

To all whom it may concern:

Be it known that I, CHARLES M. PALMER, a citizen of the United States, residing at Chicago, in the county of Cook and State of Illinois, have invented certain new and useful Improvements in Roller-Skates, of which the following is a specification.

This invention relates to roller skates, and pertains more especially to a new and improved construction of such skates designed to accelerate the speed and lessen the effort of the skater by utilizing the latter's weight wholly as a means of propulsion or as an auxiliary means of propulsion in addition to the usual skating movements.

To this end the invention comprehends, as its principal feature, the provision of slotted inclined bearings for the rear wheel of the skate, in combination with a rack and pinion mechanism as hereinafter more particularly described, whereby the weight of the skater on the heel of the skate automatically tends to propel the skate forwardly while the axle of the rear wheel is traveling through the inclined slots from front to rear, during which time the racks and pinions are engaged with each other; while, when the skater's foot is raised, the pinions are disengaged from the racks and return by gravity to the forward or lower ends of the slots.

The invention will be readily understood when considered in connection with the accompanying drawings, which illustrate an approved mechanical embodiment of the invention, wherein—

Figure 1 is a side elevational view of a roller skate equipped with my improved propelling mechanism. Fig. 2 is a cross-sectional view taken on the line 2—2 of Fig. 1. Fig. 3 is a detail view showing in inside elevation one of the supporting brackets at the rear of the skate. Fig. 4 is a cross-sectional detail on an enlarged scale through one of the rack and pinion devices on one side of the 45 skate in a plane coincident with the axis of the rear wheel. Fig. 5 is a fragmentary elevation of one of the hubs of the rear wheel with the shaft appearing in cross-section and more particularly showing the pinion. Fig. 50 6 is a sectional view on the line 6—6 of Fig. 5, with the shaft omitted.

Referring to the drawings, 10 may designate the foot-rest, 11 the heel guard, 12 the front rollers, and 13 the front brackets in 55 which the front rollers are journaled, which

parts may be of the ordinary or usual construction of metal frame skates.

Beneath the heel of the skate are a pair of depending side brackets 14 that may conveniently be stamped and pressed from a blank 60 of sheet steel, and may be formed integral with the rear section of the foot support, as shown. The lower portion of each of these brackets 14 is formed with an inclined slot 15, the metal forming the upper margin of 65 15, the slot being turned inwardly as shown at 16 in Figs. 2 and 4, and the inner edge of said inturned portion being downwardly turned and provided with a row of teeth whereby to form a rack 17. This rack terminates 70 somewhat short of the ends of the slot, in order to afford at the latter points forward and rear seats 18 and 19, respectively, for roller bearings in which the axle of the wheel may turn freely, as hereinafter more particu- 75 larly described.

20 designates as an entirety the rear wheel or roller of the skate which, as herein shown, may cheaply and strongly be formed by pressed steel sides 21 and a tread 22 interlocked with the peripheries of the side-plates, as shown. The side-plates 21 at their centers are pressed or bulged outwardly to form hubs 23, which latter are centrally apertured to receive the axle 24 passed therethrough. 80 The metal immediately surrounding the axial apertures of the hub is radially slitted to form a series of tongues, certain of which are then pressed outwardly to form pinion teeth 25, while the alternate tongues are pressed in- 85 wardly or in the opposite direction, as shown at 26 (Fig. 6) to thereby form bearings for the wheel on the shaft 24. The teeth 25 of the pinions lie in the same vertical planes with and directly engage the inclined racks 90 17 when the device is in its operative or working position, as may be seen by reference to Figs. 2 and 4. The ends of the shaft 24 are reduced, as shown at 27, and are threaded to receive nuts 28. Between the 100 nuts 28 and the shoulders formed by the reduced portions 27 of the shaft are interposed washers each of which has a cylindrical portion 29 designed to have a rolling bearing upon the under side of the inwardly turned flange 16 of the supporting bracket, and a radial flange 30 of sufficient diameter to overlap the opposite edges of the slot 15, and thus prevent longitudinal displacement of the shaft in its bearings. It will be observed 105

110

that by reason of the described construction the weight of the wearer is transmitted through the side brackets 14 and their inwardly turned flanges 16 to the shaft 24 through the cylindrical portions 29 of the washers, thereby relieving the racks and pinions of the vertical strains which might otherwise cause more or less binding and wear in the latter. It will also be observed, as 10 constituting an important feature of my device, that the slots 15 are of a width sufficiently greater than the diameter of the cylindrical portions 29 of the washers engaging said slots to permit a complete disengagement of the pinions from the racks when the washers are engaged with the lower edges of the slots on the return movement of the wheel. It is also an important feature of my device that the seats 18 at the 20 lower end of slots 15 be of such form as to hold the cylindrical portion 29 of the washers in such position that the pinions will not engage the racks when the skate is moving backward and will immediately become 25 in mesh when the skate is moving forward.

In the operation of the device, when the skater's foot is raised from the floor or ground, the wheel, together with its shaft, pinions, and roller bearing members represented by 30 the flanged washers, slides bodily on the lower edges of the slots down to the lower ends of the latter, during which movement the pinions are disengaged from the racks, as already explained. The foot being then 35 returned to the floor or ground and the skater's weight applied thereon, by virtue of the inclined slotted bearings in the heel brackets of the skate frame engaging the shaft of the rear wheel, and the coöperating 40 racks and pinions which at once come into engagement, the skate receives a forward impulse which is continuous until the shaft of the rear wheel has traveled from the lower forward ends to the higher rear ends of the 45 inclined slots. As soon as the shaft of the rear wheel reaches the latter position, the pinions run off the ends of the racks and the washers engage the rear seats 19, whereby the skate may continue the forward movement 50 under the acquired momentum or under a skating stroke of the wearer without contact or injury to the rack and pinion mechanism. As the skate is once more raised and the wearer's foot swung forward 55 the above-described operations are repeated. It will also be observed that the pinions and racks are out of engagement at the extreme lower or forward position of the rear wheel, thus permitting the pinions to enter upon 60 engagement with the racks under a relative traveling movement, and preventing the teeth of the pinions and racks from receiving the weight of the wearer when the foot is returned to the floor.

65 I am aware that it is old to employ in roller

skates the principle of inclined bearings co-operating with the shafts of the front and rear rollers of a skate, with a rack and pinion mechanism controlling the rolling movement of the shaft of the rear roller along its inclined bearing, and I do not claim the same broadly. But so far as I am aware my invention presents a novel improvement in the construction whereby the rear roller may slide back from the rear to the front of its 70 slotted bearing while the rack and pinion mechanism is disengaged, thus affording a much quicker return movement to the rear or propelling wheel than where the rack and pinion mechanism is continuously engaged; and whereby also the rear roller may turn freely at either end of the slotted bearing without injury to the rack and pinion mechanism. It will also be observed that in my improved skate the forward rollers are 80 journaled on a fixed shaft and have no rising and falling movement relatively to the skate frame. The result of this is that the heel portion of the skate frame possesses a limited 85 vertical swinging movement on the shaft of the forward rollers as a center during each 90 forward movement of the skate when in contact with the floor, the result of which is to make the inclines of the bearings of the rear roller steepest at the start and gradually decreasing or approaching the horizontal toward the end of the stroke, so that the skater receives a decided forward impulse when his weight is first applied at the beginning of the stroke, which impulse is of gradually lessening 95 force as the stroke progresses to the end. 100 As above mentioned, the skate may be used on a smooth pavement or floor by simply a walking movement, wherein the propulsive force is produced wholly by the 105 weight of the wearer; or the skate may be used in the ordinary manner of roller skates, in which case the weight of the wearer exerts additional or auxiliary propulsive force to that exerted by the usual skating movement while skating forward; and on account of the raised seats at the forward ends of the 110 inclined bearings, the pinion and ratchet gearing will not become engaged when the skate is moved backward.

115 I claim:

1. In a roller skate, the combination with a foot-supporting frame having depending brackets and front rollers journaled therein on a fixed axis of rotation, of rear brackets 120 beneath the heel portion of the skate frame having inclined slots with seats at both ends, and a rear roller the shaft whereof is mounted to have a rolling bearing in said inclined slots, substantially as described.

2. In a roller skate, the combination with a foot-supporting frame having depending brackets and front rollers journaled therein on a fixed axis of rotation, of rear brackets 125 beneath the heel portion of the skate having 130

inclined slots with seats at both ends and racks, and a rear roller the shaft whereof is mounted to have a rolling bearing in said inclined slots, said roller having pinions engaging said racks during the rolling engagement of the roller shaft in its slotted bearings, substantially as described.

3. In a roller skate, the combination with a foot-supporting frame and rollers supporting the forward end thereof, of rear brackets beneath the heel portion of the skate having inclined slots with seats at both ends and racks disposed alongside the upper edges of said slots, and a rear roller the shaft whereof is mounted to have a rolling bearing on the upper edges of said slots, said roller having pinions of substantially equal diameter with the slot-engaging portions of the shaft, said pinions engaging said racks during the rolling engagement of the roller shaft in its inclined bearings, substantially as described.

4. In a roller skate, the combination with a foot-supporting frame and rollers supporting the forward end thereof, of rear brackets beneath the heel portion of the skate having inclined slots with seats at both ends and also racks disposed alongside the upper edges of said slots, a rear roller the shaft whereof is mounted to have a rolling bearing on the upper edges of said slots, and pinions fast with said rear roller engaging said racks, said slots having a width exceeding the diameter of the roller shaft whereby said pinions are disengaged from said racks on the return or downward movement of the rear roller relatively to its slotted bearings, substantially as described.

5. In a roller skate, the combination with

a foot-supporting frame and rollers supporting the forward end thereof, of rear brackets beneath the heel portion of the skate having inclined slots the metal constituting the upper margins whereof is offset laterally to form smooth bearing surfaces and is formed along one edge of the latter with racks, a rear roller mounted between said rear brackets, the hub whereof is provided with pinions adapted to engage said racks, a shaft carrying said rear roller and extended through said slotted bearings, and washers secured on the ends of said shaft in rolling engagement with the smooth bearing surfaces of said slots, substantially as described.

6. In a roller skate, the combination with a foot-supporting frame and rollers supporting the forward end thereof, of rear brackets beneath the heel portion of the skate having parallel inclined slots each provided on its upper edge with a smooth bearing surface and seats at both ends and a rack disposed alongside thereof, a rear roller mounted between said rear brackets, the hub whereof is provided with pinions adapted to engage said racks, a shaft carrying said rear roller and extended through said slotted bearings, and washers secured on the ends of said shaft, said washers having cylindrical portions of substantially equal diameter with said pinions and in rolling engagement with the smooth bearing surfaces of said slots, substantially as described.
